(57) **CLAIM**

The ornamental design for a holder for cupping device as shown and described.

DESCRIPTION

FIG. 1 is a perspective view of a holder for cupping device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top, rear, left perspective view thereof;

FIG. 9 is a cross-sectional elevation view of the holder for cupping device of FIG. 6, taken in the direction of 9-9;

FIG. 10 is a cross-sectional elevation view of the holder for cupping device of FIG. 6, taken in the direction of 10-10; and,

FIG. 11 is a top, front, right perspective view showing the holder for cupping device in a condition of use, for clarity of disclosure.

The dash-dot-dash lines in the Figures indicate a boundary between claimed and unclaimed areas that form no part of the claimed design.

In the drawings, the broken lines shown on the holder for cupping device depicts portions of the holder for cupping device that form no part of the claimed design. In FIG. 11, the broken line showing of a cup depicts environmental subject matter only and forms no part of the claimed design.

1 Claim, 11 Drawing Sheets
